US00D468665S

(12) **United States Design Patent**
Miller

(10) Patent No.: **US D468,665 S**
(45) Date of Patent: ** Jan. 14, 2003

(54) **TWO-PIECE THROTTLE CABLE ADAPTOR FOR SNOWMOBILES**

Drag Spealties Cat. 1995—p. 383—support bracket at center right.*

(76) Inventor: **James R. Miller**, 529 S. Lavina, Sandpoint, ID (US) 83864

* cited by examiner

(**) Term: **14 Years**

Primary Examiner—Nelson C. Holtje

(21) Appl. No.: **29/147,619**

(74) Attorney, Agent, or Firm—Jensen & Puntigam, P.S.

(22) Filed: **Aug. 30, 2001**

(57) **CLAIM**

(51) LOC (7) Cl. **12-14**

The ornamental design for a two-piece throttle cable adaptor for snowmobiles, as shown and described.

(52) U.S. Cl. **D12/7; D12/174**

DESCRIPTION

(58) Field of Search D12/7, 174, 179, D12/114, 177; 180/335

(56) **References Cited**

FIG. 1 is an isometric view of a two-piece throttle cable adaptor for snowmobiles showing my new design; FIG. 2 is a front elevational view thereof; FIG. 3 is a right side elevational view thereof; FIG. 4 is a rear elevational view thereof; FIG. 5 is a left side elevational view thereof; FIG. 6 is a top plan view thereof; and, FIG. 7 is a bottom plan view thereof.

U.S. PATENT DOCUMENTS

The broken line showing of fasteners in FIG. 1 is for illustrative purposes only and forms no part of the claimed design.
